United States Patent Office.

JOHN MEGOWN, OF NEW LONDON, MISSOURI.

Letters Patent No. 63,074, dated March 19, 1867.

IMPROVEMENT IN CHURNS.

The Schedule referred to in these Letters Patent and making part of the same.

TO ALL WHOM IT MAY CONCERN:

Be it known that I, JOHN MEGOWN, of New London, in the county of Ralls, and State of Missouri, have invented a new and useful Improvement in Churn; and I do hereby declare that the following is a full, clear, and exact description thereof, which will enable others skilled in the art to make and use the same, reference being had to the accompanying drawings, forming a part of this specification, in which—

Figure 1 is a vertical longitudinal section of my improved churn, taken through the line *x x*, fig. 1, and showing in red lines the position of the parts when the cover is raised.

Figure 2 is a vertical cross-section of the same taken through the line *y y*, fig. 1.

Similar letters of reference indicate like parts.

My invention consists in the construction of the churn, and in the combination and arrangement of the operating parts with each other and with the hinged lid of the churn, so that the said operating parts may be removed from the churn and out of the way by simply raising and turning back the said hinged lid as herein-after more fully described.

A is the bench or platform upon which the bottom of the churn rests. *a'* is a strip that may be attached to the said platform to guide the churn into the proper position to receive the hinged lid. *B* is the body of the churn, the bottom and sides of which are made of zinc, and it is made in substantially the shape shown in the drawings, so that it may have no sharp corners or angles in which particles of curd or other impure matter may collect and be difficult to be cleaned. The ends *b'* may be made of wood to give shape and stiffness to the churn, and the upper edges of the sides may be stiffened by strips *b''* of wood, as shown in fig. 1. To one end of the platform *A* are attached the lower ends of the uprights *c'* of the frame *C*. These uprights are of the same height as the body *B* of the churn, and to their upper ends is securely attached the cross-piece *c''*, to which the lid *D* is hinged, as shown in fig. 1. The lid *D* shuts down over the top of the churn, and has a flange, *d'*, formed upon or attached to its under side which fits into the mouth of said churn, and at the same time insures the churn being in proper position and guards against any spattering of cream or milk. To the central part of the rear end of the lid *D* is securely attached the lower end of the curved support or standard *E*, the curve of which should be sufficient to bring its forward or upper end a little in front of the centre of said lid, as shown. The standard *E* is slotted, as shown in fig. 2, to receive the driving-pulleys *F* and *G*. The pulley *F* being the larger is placed in the lower part of the said slot, and is attached to the shaft *H*. The shaft *H* revolves in bearings attached to the sides of the standard *E*, and to one of its ends is attached the crank *I*, by means of which the churn is operated. The wheel or pulley *G* is attached to the shaft *J*, to the ends of which are attached, or upon the ends of which are formed, cranks, *K*, as shown in fig. 2. Motion is communicated from the pulley *F* to the pulley *G* by means of the cord or band *L*, as shown. Or, if desired, the pulleys *F* and *G* may be replaced by gear-wheels, the cogs of which mesh into each other; but I prefer the manner first described. The shaft *J* passes through and works in a slot formed in the sides of the standard *E*. The shaft *J* is supported by the box or cap *M*, which is suspended from the upper end of the standard *E*, by the screw-bolt *N*, and hand-nut *O*. By raising or lowering the said nut *O*, the pulley *G* is lowered or raised, slackening or tightening the cord or band *L* as required. *P* are the dasher-handles, the upper ends of which are pivoted to the cranks *K*; they pass thence through holes in the lid or cover *D*, and to their lower ends are attached the dashers, about the construction of which there is nothing new. *S* is an air hole formed in the centre of the lid *D*, and which may be closed when desired by a plug, *T*, as shown. *d''* is a ledge or flange formed around the holes in the lid *D*, through which the dasher-handles *P* pass. This ledge is designed to confine the milk that is raised from the churn by the said dasher-handles and allow it to flow back again. This construction and arrangement allow the whole operating parts of the churn to be raised out of the way by simply raising and turning back the hinged lid *D*. And when thus raised the said parts are in the most favorable position for being washed and cleaned.

Having thus described my invention, I claim as new, and desire to secure by Letters Patent—

1. The combination and arrangement of the pulleys *F* *G*, and band *L*, or their equivalent, shafts *H* *J*, cranks *I* *K*, standard *E*, and hinged lid *D* with each other, and with the dasher-handles *P*, churn *B*, and frame *C*, substantially as described and for the purpose set forth.

2. The combination of the box or cap *M*, bolt *N*, and nut *O*, with the shaft *J*, and standard *E*, substantially as described and for the purpose set forth

JOHN MEGOWN.
